CLAIM

The ornamental design for the handheld remote controller, as shown and described.

DESCRIPTION

FIG. 1 is a perspective view of a handheld remote controller showing our new design.

FIG. 2 is a right-side perspective view thereof.

FIG. 3 is a left-side perspective view thereof.

FIG. 4 is a front perspective view thereof.

FIG. 5 is a rear perspective view thereof.

FIG. 6 is a top perspective view thereof; and,

FIG. 7 is a bottom perspective view thereof.

The broken lines depict portions of the handheld remote controller that form no part of the claimed design.
